UNITED STATES PATENT OFFICE.

HENRI JULES MALADRY, OF PARIS, FRANCE.

GAS-HEATED WATER-HEATING APPARATUS.

Application filed January 18, 1922. Serial No. 530,153.

To all whom it may concern:

Be it known that I, HENRI JULES MALADRY, a citizen of the French Republic, residing at Paris, France, have invented new and useful Improvements in Gas-Heated Water-Heating Apparatus, of which the following is a specification.

The present invention relates to a gas-heated water-heating apparatus intended to heat water in sufficient quantity to supply the basin of a wash-stand, or to supply intermittently small quantities of water at a predetermined temperature.

The said apparatus comprises a vessel provided with an inlet for cold water at the pressure of the main or at a lower pressure and with a water outlet for either hot or cold water at will. To this end, a special cock makes it possible either to allow the water to flow directly towards the outlet or to cause same to circulate within the vessel, where it is heated by a flame of gas provided in the lower portion of a central flue round which the water circulates in a well known manner.

The water is heated to a predetermined maximum temperature by means of an automatic regulating device which is combined in such a way as to cut off the gas supply as soon as the temperature of the water rises above the normal (for instance 65° centigrade) and as to re-establish the gas supply as soon as the temperature becomes lower than normal.

In order that the invention may be readily understood, an embodiment of same is, by way of example only, illustrated by the accompanying drawings, in which:

Fig. 1 is a vertical section through a water heating apparatus according to the invention, the parts being in position to obtain cold water,

Fig. 2 is a detailed section showing the special three-way-cock which makes it possible to obtain either cold or hot water, the parts being in position for the hot water supply,

Fig. 3 is a vertical section at an enlarged scale of the automatic regulating device.

In the aforesaid drawings, 1 designates the body of the apparatus, which is preferably cylindrical and is provided with a central flue 2 in the base portion of which is located a burner 3 for blue flame gas, fitted on the end of the pipe 4. The latter has the regulating device 5 fitted thereon and is con-

trolled by means of the cock 6, arranged below the outlet of the purifier 7.

Adjacent the burner 3 for blue flame gas is located a small permanent burner 8 for lighting the gas of the burner 3 and of which the supply pipe 9 is connected to the main gas pipe 4 at a point situated between the cock 6 and the regulating device 5.

10 designates the cock or valve controlling the supply of water under pressure, the said cock or valve 10 being connected to the inner tube 11 which leads to the three-way-cock 12 which is in turn connected to one end of a curved tube 13 of which the other or free end delivers under a jet-breaker 14. The three-way-cock 12 is further connected to a vertical tube 15 of which the upper end is bent downwardly and delivers into a tube 16 which is connected to the outer outlet 75 pipe 17. It will be readily understood that if the three-way-cock 12 is in the position shown in Fig. 1, the outlet-pipe 17 will deliver cold water passing by way of the tube 15 and the tube 16. If on the contrary the 80 cock 12 is rotated and set in the position indicated in Fig. 2, the cold water passes by way of the tube 13 and goes thence towards the bottom of the apparatus, in the annular space existing between the outer casing 1 85 and the central flue 2. This water is thus heated by the contact of the flue and, being subjected to the pressure of the cold water, rises towards the top of the vessel 1, to be evacuated by way of the tube 16. The outer 90 outlet-pipe 17 then delivers hot water.

The regulating device 5, arranged at the level of the jet breaker 14, automatically maintains the water supplied by the heating apparatus at a predetermined maximum 95 temperature, for instance 65° centigrade. The said device comprises a thermostatic capsule 18 (Fig. 3) containing for instance methylated spirits, of which the boiling point is about 66° centigrade. This capsule 18 acts in a well known manner on a dish-like member 19 slidably mounted in a suitable guide 20 and which operates a piston or plunger 21 which in turn operates an obturator or valve 22. The latter is subjected to the action of a spring 23 and is provided with a central guiding rod 22^a which is able to slide in a corresponding recess of the casing 5. The gas is admitted by way of the passage or port 5^a and leaves 110 the regulating device by means of the passage or port 5^b. The passage of the gas is

thus allowed or cut off according to the position of the obturator or valve 22. It will be readily understood that if the thermostatic capsule 18 is dilated by the heat 5 when the temperature rises above the pre-determined maximum, it will push the dish-like member 19 and the valve 22 which will then be applied on its seat and will thus cut off the passage of the gas by closing the admission port 5^a. Only the small burner 8 will then remain lit. The cold water on reaching the jet-breaker 14 exactly opposite the thermostatic capsule 19, instantaneously cools the latter which through its 10 contraction allows the valve 22 to open again under the influence of the spring 23 so as to permit the passage of the gas, which is lit again by the contact of the small flame from the permanent burner 8. The required temperature is therefore re-established, and the 15 operation is repeated in the same manner as often as required, owing to the automatic operation of the regulating device 5, which thus controls the temperature of the water 20 delivered by the outer outlet pipe 17.

I claim:

In a thermostatic valve for gas-heated water-heating apparatus, the combination of: a valve casing (5), forming an annular 25 chamber and having an admission port (5^a) and an exit port (5^b) for the gas; a cup-

shaped valve (22) having a central stem (22^a), mounted within said casing and adapted to control the passage of the gas therethrough from the admission port towards the exit-port; a guiding sleeve for said central stem, integral with said casing; a coil-spring (23) arranged in the aforesaid cup-shaped valve and normally tending to keep same away from its seat; a stationary cup-shaped guide-member (20) mounted laterally in the wall of the valve-casing coaxially and back to back with the cup-shaped valve and having an integral central sleeve; a piston (21) extending within the last-named sleeve and having one end in operative contact with said cup-shaped valve; a flanged dish-like member (19) slidably mounted in the aforesaid stationary guide-member and in operative contact with the other end of said piston; and a thermostatic capsule expansible by heat (18), having one face in operative contact with the said dish-like member; substantially as described.

In testimony whereof I signed hereunto my name in the presence of two subscribing witnesses:

HENRI JULES MALADRY.
